UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,204,708.

Specification of Letters Patent. Patented Nov. 14, 1916.

Application filed September 26, 1914. Serial No. 863,664.

To all whom it may concern:

Be it known that I, WILLIAM A. SMITH, a citizen of the United States, residing at Denver, in the county of Denver and State 5 of Colorado, have invented new and useful Improvements in Rock-Drills, of which the following is a specification.

The present invention relates to rock drilling apparatus, and one of the primary objects is to provide a novel and effective means for delivering a cleansing agent to the bore of a hollow drill bit, for the purpose of removing the cuttings from the drill hole.

15 A further and important object is to provide novel and effective means for rotating the drill bit, this means being positive in action, and yet permitting the parts, with the exception of the drill chuck, to continue in 20 operation should the drill bit become stuck, thereby avoiding the danger of injury and breakage to the mechanism.

An embodiment of the invention that has proven very satisfactory, is disclosed in the 25 accompanying drawings, wherein:—

Figure 1 is a side elevation of the apparatus. Fig. 2 is a plan view partially in horizontal section. Fig. 3 is a front end view with a portion of the chuck casing 30 broken away. Fig. 4 is a detail longitudinal sectional view on a somewhat enlarged scale. Fig. 5 is a detail view partially in section of the coöperating shafts of the chuck rotating means. Fig. 6 is a detail 35 perspective view of the friction gear. Fig. 7 is a similar view of the rotating shaft. Fig. 8 is a detail view on an enlarged scale of the pawl and ratchet mechanism that prevents the retrograde movement of the 40 ratchet member. Fig. 9 is a detail perspective view partially broken away of the drill chuck. Fig. 10 is a perspective view of the end of the rock shaft having the ratchet teeth, and Fig. 11 is a perspective view of 45 the coacting ratchet member. Fig. 12 is a rear elevation of the crank case, showing the operating handle for the by-pass controlling valve.

Similar reference numerals designate cor- 50 responding parts in all the figures of the drawings.

In the embodiment disclosed, a support is employed in the form of a shell 10, and 55 slidably mounted in guideways 11 of said shell, is a carriage 12 that may be moved

through the medium of the usual screw, having a handle crank at the rear end, as shown at 13. Mounted on the carriage 12, is the drilling apparatus, and in the embodiment disclosed, this includes a compressor 60 and a motor. The compressor includes a cylinder member 14 containing a piston 15 having a piston rod 16 projecting therefrom, and this piston rod is connected by a pitman 17 with the crank or wrist pin 18 of 65 a counterbalanced head disk 19. The disk 19 has secured to its inner face, a ring 20 provided with internal gear teeth 21 and an external ball-race 22. Engaged in said race 22 are anti-friction balls 23 that are 70 also engaged in an outer race-way 24 mounted in the flange 25 of the head 26 of an electric motor 27. The armature 28 of this motor is mounted on a shaft 29, carrying a pinion 30 that is in mesh with the internal 75 gear 21. It will thus be seen that if the motor is in operation, the gear 21 will be rotated, thereby effecting the operation of the crank 18, and through the medium of the pitman 17, the compressor piston 15 will be 80 reciprocated.

The drill motor comprises a cylinder member 31, within which is located a free hammer piston 32 that is driven back and forth by the air alternately compressed on 85 opposite sides of the piston 15 during its reciprocation. This air is supplied from the compressor cylinder 14 to the motor cylinder 31 on opposite sides of the piston 32 by 90 passages 33 and 34, the passage 34 having a front port 35 and a rear port 36 that is in the form of a circular groove in the inner face of a rear head bushing 37. Relief channels 37^a are connected with the said passages and ports. The rear port 36 is controlled by 95 a forwardly opening valve 38 mounted on a spindle 39 secured in the bushing 37 by a nut 40 threaded upon its rear projecting end. This valve constitutes, in effect, a check valve, and it has a hub portion 41 100 slidably mounted on a reduced portion of the spindle 39, the hub having an inturned flange 42 at its inner end. The front end of the spindle 39 has an outstanding flange 43, and a spring 44, interposed between the flanges 42 and 43, serves to urge the valve to closed position. In the outer wall of the cylinder member 14 is formed a by-pass 105 comprising a longitudinal passageway 45 having end ports 46 opening into the ends 110

of the piston chamber. This by-pass is controlled by a rotary valve 45^a mounted longitudinally in the passageway 45, and having a longitudinal bore 46^a therein, this bore 5 communicating with transverse ports 45^b that are movable into and out of register with the ports 46. The valve is operated by a shaft 46^b having an angular end 45^c that engages in a corresponding socket in the 10 rear end of the valve and being held therein by a coiled spring 46^c. The rear end of the shaft 46^b projects through the rear end of the crank case, which crank case is designated 45^d, and the projecting end has an 15 operating handle 46^d that is movable between two stops 45^e.

The front end of the cylinder member 31 is provided with a head bushing 47, over 20 which is mounted a cap 48 that contains a rotatable drill-holding chuck 49. Said chuck 25 has a socket 50 arranged to detachably receive the rear end of a tool 51, said tool having an angular enlargement 52 engaged in the chuck so as to cause the two to rotate together. The tool is provided with a passageway 53 therethrough, for the purpose 30 of delivering cleaning fluid to the bottom of the drill hole. A tappet 54 is slidably mounted in the head bushing 47, its inner 35 end projecting into the cylinder member 31 in a position to be struck by the piston 32, its outer end being abutted against by the rear end of the drill bit 51. In order that the abutting faces of the tappet and drill 40 bit may also be in proper contact to obviate leakage of the cleansing fluid, a spring 55 is interposed between the flanged front end 56 of said tappet and a shoulder 57 formed upon the head bushing 47, said spring thus urging the tappet forwardly.

For the purpose of delivering cleansing fluid to the bore 53 of the drill bit 51, a tube 58 extends longitudinally and centrally through the cylinder 31, through the piston 32, and into the tappet 54, terminating short 45 of the front end of said tappet, this tube also extending through a central bore formed in the valve supporting spindle 39, and its rear end is mounted in the rear head 50 of the cylinder member 31, being held in 55 place by yielding packing 60 surrounding the same, said packing being compressed about the rear end of the tube by a plug 61, as will be readily understood. The cleansing fluid is supplied from any suitable source to a coupling socket 62 formed in the head 59, and is delivered through a passageway 63 formed partly in the head 59 and partly in the plug 61.

60 As above stated, the chuck 49 is rotatable, and the following mechanism is preferably employed for securing its rotation when the drill is in operation. Journaled alongside the cylinder member 31 and below the cylinder member 14, is a rotatable shaft 64 hav-

ing a tapered front portion 65 and an angular rear end 66. Mounted on the tapered portion 65, is a bronze bushing 67, surrounding which is the elongated hub 68 of a gear pinion 69, that thus has a frictional bearing or mounting on said shaft. It is held in place by nuts 70 threaded on the front end of the shaft 64, with spring washers 71 interposed between said nuts and the end of the gear pinion. The pinion 69, 70 in the embodiment disclosed, is in mesh with an idler pinion 72, which in turn meshes 75 with gear teeth 73 formed upon the rear end of the chuck sleeve, as shown clearly in Fig. 9.

80 Journaled in alignment with the shaft 64, and arranged in rear thereof, is a rock shaft 74, having its front end formed into ratchet teeth 75. A ratchet member 76, slidably mounted on the angular end 66 of the shaft 85 64, and held thereby against relative rotation with respect to said shaft 64, has teeth 77 that are movable into and out of coaction with the teeth 75. A coiled spring 78, bearing 90 against the member 76, urges it rearwardly, so that the teeth 77 will coact with the teeth 75. The member 76, furthermore, has a peripheral series of ratchet teeth 79, with which a spring-pressed pawl 80 operates to prevent the retrograde rotation 95 of the member 76 and shaft 64.

100 The rear end of the rock shaft 74 has a beveled gear section 81, with which meshes a corresponding beveled gear section 82 carried by the inner end of a crank shaft 83 that is journaled in the frame, the outer end of the crank shaft 83 carrying a crank 84. This crank 84 is pivotally connected, as 105 shown at 85, to a pitman 86 mounted in a socket 87 formed in the outer face of the pitman 17, said pitman 86 being pivotally connected, as illustrated at 88 to said pitman 17.

110 The operation of the structure is substantially as follows:—When the motor 27 is in operation, the compressor piston, as already described, is reciprocated, causing the air under compression to be alternately delivered into the cylinder 31 on opposite sides of the piston 32, and causing the reciprocation of said piston. At each forward movement of the piston, a blow is struck against the tappet 54, and said blow is transmitted to the drill bit. Inasmuch as the pitman 17 is given a rapid gyratory movement, the pitman carried thereupon is given a corresponding movement. Consequently the crank shaft 83 and rock shaft 74 are turned back and forth. The teeth 75 of the rock shaft, upon their rearward movement, pass over the teeth 77 of the ratchet member 76, 115 said member sliding forward on the shaft 64 until the teeth 75 have passed, whereupon the member 76 is returned by the spring 78, and the two sets of teeth are interlocked. Upon the return movement, therefore, the 120

125 130

shaft 64 is given a partial rotation, and therefore said shaft has a step-by-step rotation while the motor is in operation. This motion is transmitted through the gearing 5 69, 72 and 73 to the chuck, and consequently to the drill bit located therein. If such drill bit should become stuck, the frictional mounting of the pinion 69 upon the shaft 64 will permit said shaft to slip, and thus obviate the danger of injury to the remaining parts of the mechanism. It is often the case, moreover, that the cuttings will become packed around the drill bit, making it exceedingly difficult to withdraw the same 10 from the hole. With the present structure, this can be readily accomplished, for by turning the valve 46^a, so that the by-pass 46 is open, the motor piston 32 will be substantially stopped while the rotation of the drill 15 bit continues, and consequently by turning the feed screw rearwardly, by means of the handle 13, the drill bit will bore its way out through the packed cuttings as the machine is withdrawn.

20 25 The cleansing agent, as already explained, is delivered to the drill bit through the tube 58, and because of the relatively tight joint maintained between the tappet and the rear end of such drill bit by the spring 55, there 30 is little leakage at this point.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the 40 advantages of the invention.

Having thus fully described my invention, what I claim as new, and desire to secure by Letters Patent, is:

1. In drilling apparatus, the combination 45 with a motor, comprising a cylinder member and a piston operating therein, of a compressor comprising a cylinder member and a piston operating therein, means for driving the compressor piston, including a pitman, a tool-holding chuck, and means actuated by said pitman for rotating the chuck.

2. In drilling apparatus, the combination 50 with a motor, comprising a cylinder member and a piston operating therein, of a compressor comprising a cylinder member and a piston operating therein, means for driving the compressor piston, including a pitman, a tool-holding chuck, and means operated by said pitman for effecting a step-by-step rotation of the chuck.

3. In drilling apparatus, the combination 55 with a motor, comprising a cylinder member and a piston operating therein, of a compressor comprising a cylinder member and a piston operating therein, means for driving

the compressor piston, including a pitman, a rotatable tool-holding chuck, a shaft geared thereto, ratchet mechanism for rotating the shaft, and means actuated by the pitman for operating the ratchet mechanism.

4. In drilling apparatus, the combination with a motor, comprising a cylinder member and a piston operating therein, of a compressor comprising a cylinder member and a piston operating therein, means for driving 70 the compressor piston, including a pitman, a rotatable tool-holding chuck, a shaft geared thereto, a ratchet element on the shaft, a rock shaft having a coacting ratchet element, and means operated by the pitman for rocking 75 said shaft.

5. In drilling apparatus, the combination with a motor, comprising a cylinder member and a piston operating therein, of a compressor comprising a cylinder member and a piston operating therein, means for driving 80 the compressor piston, including a pitman, a rotatable tool-holding chuck having gear teeth thereon, a shaft geared to said gear teeth, a rock shaft in line with the first-mentioned shaft, a ratchet connection between the two shafts for imparting a step-by-step rotation to the former upon the rocking movement of the latter, a crank shaft geared to the rock shaft, and a pitman connection 85 between the compressor pitman and the crank shaft.

6. In drilling apparatus, the combination with a cylinder member, of a piston operating therein, a rotatable tool-holding chuck, 90 a shaft, a slip gear connection between the shaft and chuck that permits their relative rotation under abnormal resistance, and a ratchet mechanism for rotating the shaft.

7. In drilling apparatus, the combination 95 with a cylinder member and a piston operating therein, of a rotatable tool-holding chuck, a shaft having a tapered end and an angular end, a gear frictionally mounted on the tapered end and geared to the chuck and permitting the relative rotation of the shaft and gear under abnormal resistance, a ratchet element mounted on the angular end, another ratchet element coacting with said first-mentioned element, and means for giving 100 the second element an oscillatory movement.

8. In drilling apparatus, the combination with a cylinder member and a piston operating therein, of a rotatable tool-holding 105 chuck, a shaft arranged longitudinally of the cylinder member, a gear frictionally mounted on one end of the shaft and geared to the chuck, a ratchet member slidably mounted on the other end of the chuck and held thereon against relative rotation, a rock shaft having a ratchet member coacting with the first-mentioned ratchet member, and means for imparting a back-and-forth movement to the rock shaft.

9. In drilling apparatus, the combination with a motor, comprising a cylinder member, a piston and a rotatable chuck, of a compressor, including a piston, a driving motor for the compressor, a connection between the driving motor and the compressor piston having a back-and-forth movement, a rotatable device geared to the chuck, and ratchet mechanism operated by said connection and operating on the rotatable device, to effect a step-by-step rotation thereof.

10. In drilling apparatus, the combination with a motor, comprising a cylinder member, a piston operating therein, and a rotatable tool-holding chuck, a shaft located longitudinally of the cylinder member and having a slip gear connection with the chuck, a rock shaft aliued with the first-mentioned shaft and having a ratchet connection therewith, and means for turning the rock shaft back and forth.

11. In a drilling apparatus, the combination with a motor, of a hammer cylinder, a compressor piston, an internal gear being

mounted on said motor head by an annular 25 ball race, a crank disk being mounted on said internal gear and a channeled pitman having a rocker shaft pitman inserted in its channel, a connection between the channeled pitman and the piston, and tool rotating means op- 30 erated by the rocker shaft pitman.

12. In a drilling apparatus, the combination with a cylinder member, of a piston operating therein, a rotatable tool holding chuck, a shaft, a slip gear connection be- 35 tween the shaft and chuck to permit their relative rotation under abnormal resistance, said slip gear being mounted with a friction metal bushing between said slip gear and shaft.

40 In testimony whereof I have hereunto set my hand in presence of two subscribing witnesses.

WILLIAM A. SMITH.
